UNITED STATES PATENT OFFICE.

CHARLES A. CAMPBELL, OF NEW YORK, N. Y.

REFLECTOR.

1,361,365.

Specification of Letters Patent.

Patented Dec. 7, 1920.

Application filed August 23, 1919. Serial No. 319,360.

To all whom it may concern:

Be it known that I, CHARLES A. CAMPBELL, a citizen of the United States, and residing at New York, New York county, and New 5 York State, have invented certain new and useful Improvements in Reflectors, of which the following is a specification.

This invention relates to reflectors and more especially to sheet metal or similar 10 disks with a reflective surface and having a central opening and resilient fingers around the same, the object of the invention being to place and adjust the disk on the shank of an electric light bulb and the whole within 15 in a glass or porcelain globe, as will be more fully described in the following specification, set forth in the appended claims and illustrated in the accompanying drawings wherein:

20 Figure 1 is a vertical sectional view through an electric light globe showing the reflector in section,

Fig. 2 is a plan view of the reflector,

Fig. 3 is a side elevation of the same showing it applied to the shank of a bulb.

25 Fig. 4 shows a modified form of reflector and where the same is made concave.

In the translucent or transparent globes, and particularly the former and which in 30 closes an incandescent electric lamp, a great deal of the light rays are absorbed in the metal cap which closes the opening to the globe and its distance from the filament and irregular shape make it incapable of performing the reflection function. As a consequence, a great amount of the lighting 35 power of the lamp is wasted and only the direct rays from the lamp are thrown on and through the globe.

40 To utilize the upper part of the globe 5, for reflective purposes, the bulb 6, carries on its shank 7, the disk 8, preferably of flexible metal and having a reflective surface on one or both of its sides. At its center is an 45 opening 9, through which the shank passes and from the edges of this hole are cut the fingers 10, the incisions for the cut penetrating the disk for about half the length of the fingers and to strengthen the latter at the

50 points where the most strain is put upon them, they are made wedge shaped so that the base or point of attachment 11, is of maximum width to bear the strain while sprung on the shank.

As shown in Fig. 1, the reflector is of a 55 diameter that permits its entrance through the opening 12 of the globe and the whole device is assembled by applying the disk 8, to the shank 7, when the fingers will spring upward and create enough friction to remain where originally located. The plug 13, is then screwed into the cap 14, and the latter secured about the head 15, by the screws 16.

By adjusting the disk up or down the 60 shank, the proper distance may be secured for its most efficient service as a reflector and, as shown in Fig. 3, it may be set at an angle when it is desired to throw the rays in any particular direction.

70 The disk also protects the cap 14, from the heat of the light rays to which it would be otherwise exposed and consequently prevents the deterioration of the same and undue expansion and contraction, at the same 75 time, the danger from fire, in consequence of excessive heat, is eliminated.

It is obvious that the disk may be dished in order to concentrate the light rays and that other modifications and arrangements 80 may be resorted to without departing from the essential features above described.

What I claim as new is:

1. In a reflector, the combination of lighting means having a shank, a disk with an 85 opening adapted to fit about the shank and adjustable at various angles thereon, and fingers at the edges of the opening and adapted to engage the said shank and hold the reflector at the desired angle. 90

2. In a reflector, the combination of lighting means having a shank, a disk having a central opening to fit about the shank, and fingers cut from the disk and within the edge of the central opening and adapted to 95 resiliently engage the said shank and hold the disk at any desired angle.

In testimony whereof, I have signed my name to this specification in the presence of two subscribing witnesses, this 19 day of 100 August 1919.

CHARLES A. CAMPBELL.

Witnesses:

JAMES F. DUHAMEL,
WILLIAM F. DOLL.
